(57) **CLAIM**

The ornamental design for a video conferencing system, substantially as shown and described.

DESCRIPTION

FIG. 1 is a perspective view of a video conferencing system in an open position, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a bottom perspective view thereof; and,

FIG. 10 is another bottom perspective view thereof.

The broken lines show portions of the video conferencing system that form no part of the claimed design.
